CLAIM

The ornamental design for portable x-ray film printer for imprinting patient information or the like on unexposed portion of x-ray film, as shown and described.

DESCRIPTION

FIG. 1 is a perspective view of a portable x-ray film printer for imprinting patient information or the like on unexposed portion of x-ray film showing my new design in non-operating mode;

FIG. 2 is a top plan view thereof in operating mode;

FIG. 3 is a right side elevational view thereof;

FIG. 4 is a front elevational view thereof;

FIG. 5 is a left side elevational view thereof;

FIG. 6 is a bottom plan view thereof; and

FIG. 7 is a rear elevational view thereof.
